TRACK FOR SLIDING DOORS

Joseph H. Borden, Toledo, Ohio, assignor to
Haughton Elevator Company, Toledo, Ohio, a
corporation of Ohio

Application September 14, 1948, Serial No. 49,253

2 Claims. (Cl. 16—96)

1

This invention relates to elevator door hanger mechanisms and, more particularly, to mechanism for insulating in the hanger, the vibration normally resulting when an elevator door is supported on metal wheels running on metal tracks.

It is the principal object of this invention to provide a hanger wheel which is vibrationally insulated from the hanger and the door which the hanger supports and a track for the wheel which is vibrationally insulated from the main structural elements of the elevator.

It is another object of this invention to provide a vibrationally insulated track for an elevator hanger wheel where the rail is insulated from the mounting means by an interposed cushioning member and in which the rail mounting means and cushioning member are all assembled relative to each other by a telescoping operation thereby eliminating any direct metallic contact between the several members of the track.

These and other objects will be apparent from the drawings, in which:

Figure I is a view in elevation, partly broken away and somewhat conventionalized, of an elevator cab having two center parting doors supported by hanger mechanism embodying the invention.

Figure II is a greatly enlarged fragmentary isometric view taken from the lower inner side of one of the door hangers.

Figure III is a similar view but of idler pulley mechanism located at one of the outer ends of the hanger track.

Figure IV is a vertical sectional view on an enlarged scale taken substantially from the position indicated by the line IV—IV in Figure I.

Figure V is a fragmentary view in elevation taken from the left side of Figure IV and showing a hanger upthrust bearing.

A conventional elevator cab usually consists of a framework around which is erected panelling which encloses the cab and which usually is decorated on its interior surface. The elevator cab, indicated by the reference numeral 1 in Figure I, has laterally extending shoes 2 which slide on vertically extending rails 3. The cab is lifted by one or more cables 4 which extend upwardly to the elevator machinery usually located in a machine room at the top of the building in which the elevator is installed.

Elevators often are equipped with center parting double doors 5 and 6 which operate in conjunction with floor landing doors (not shown). The elevator doors 5 and 6 are actuated for lateral

2

movement so that when the elevator is stopped the two doors move outwardly simultaneously reaching their full open position at the same time and, when being closed, meeting at the center of the doorway. The combined width of the two elevator doors must be slightly less than one-half of the full width of the elevator so that there will be room at the side of the door opening for the doors when they are open.

10 In Figure I the doors 5 and 6 are shown as being each supported by two hangers, an inner hanger 7 and an outer hanger 8. Each of the hangers 7 and 8 is bolted or otherwise secured to the upper edge of its respective door 5 or 6. Each of the hangers 7 and 8 is equipped with a wheel 9 which runs upon a track 10, the track 10 in turn being supported upon a bracket 11 which is secured to a main crossframe member 12 of the cab.

15 In the center parting door construction shown in Figure I the simultaneous operation of the doors is insured by an "endless" cable 13 which is secured to each of the inner hangers 7 and extends laterally to the ends of the elevator frame where it passes around a pair of idler pulleys 14, one of which is located at each end of the bracket 11. The cable 13, as shown in Figure 1, may include turnbuckles 15 or similar devices for maintaining tension in the cable. In most center parting door installations only one of the doors is connected to the door opening mechanism which usually is mounted on top of the elevator cab. For simplification, this mechanism is not shown, since it does not constitute part of the instant invention.

20 In Figure II an outer hanger 8 is shown on a substantially larger scale and with certain parts of its component parts broken away and in section so that the structure of the device can be explained. To the top edge of the door 5 there is secured by means of bolts 16 the lower horizontal flange of a hanger bracket 17 which constitutes the main structural member of the hanger 8. The hanger wheel 9 is rotatably mounted upon a stub axle 18 which extends inwardly from the hanger bracket 17. The stub axle 18 has a flanged portion 19 at its outer end which positions it relative to the hanger bracket 17 and also positions the edge of an inner race 20 of a wheel bearing 21. The wheel bearing 21 is secured on the axle 18 by a split ring 22 which is snapped in a groove 23 cut in the outer end of the axle 18 on the outer side of the inner race 20. The wheel 9 has a center bore 24 which is 25 provided with a lip 25 at its inner end. The

bearing 21 has an outer race 26 which is positioned between the flanges of a U-shaped annular vibration absorbing element 27. The vibration absorbing element 27 fits tightly in the bore 24 and against the lip 25 of the wheel 9. The vibration absorbing element 27 and the bearing 21 are held in the wheel 9 by an annular retainer 28. The retainer 28 fits snugly within the bore 24 and is held in place by swedging the metal together as indicated by the numeral 29.

The periphery of the wheel 9 is grooved and rides upon the cylindrical surface of a rail 30 which is mounted in a rail retainer 31 in turn supported upon a mounting member 32 which is secured to a lower outwardly turned flange 33 of the bracket 11. The rail 30 and its retainer 31 both are made of metal. The retainer 31 preferably is extruded from a soft metal, such as brass, the rail 30 being made of a hard metal such as stainless steel rod. The retainer 31 has two upwardly extending arms 34 which embrace the rail 30 extending beyond its center line to retain it fixedly in the retainer. The lower portion of the retainer 31 is formed into two substantially L-shaped flanges 35 which extend downwardly and inwardly. The upper portion of the mounting member 32 is formed in a T-shaped flange 36, the horizontal crossarm of the T lying between and above the horizontal portions of the flanges 35. The mounting member 32 also preferably is an extruded piece, again being made of a soft metal.

Between the flanges 35 of the retainer 31 and the flange 36 of the mounting member 32 there are located a pair of approximately C-shaped vibration absorbing cushions 37 which, again, are extruded, but in this instance are made of relatively soft rubber. The cushions 37 extend between the adjacent sides of the flanges 35 and 36 and the base of the mounting member 32.

The track as a whole, i. e., including its components the rail 30, retainer 31, mounting member 32 and cushions 37, is assembled from pieces of the several members, each of which extends the full width of the elevator. By virtue of the design just explained the pieces can all be made of extruded material with the exception of the rod-like rail 30. The various parts are assembled by first lubricating them with some material such as stearic acid or soap and then telescoping the members relative to each other until the assembly has been accomplished. It will be noted that the flanges 35 and 36 are of such size that they do not contact each other in any place and that where the cushions 37 do not extend, there is left an approximately C-shaped open space 38 extending above the top of the crossarm of the T-shaped flange 36 and along the inner sides of the vertical arms of the L-shaped brackets 35. There is thus provided clearance between the rigidly mounted member 32 and the track retainer 31 so that the two members can move angularly relative to each other without engagement with the angular movement resisted by the resilience of the cushions 37. The rubber material from which the cushions 37 are made is selected to have a degree of resistance to compression sufficient to prevent engagement between any portions of the mounting member 32 and the retainer 31 except under most unusual conditions.

At the upper corner of the hanger 8 farthest removed from the stub axle 18 there is located an upthrust roller 39 which consists merely of a ball bearing having an outer race made of a hard

metal and which is mounted upon a stud 40 fixed on a small offset plate 41 by means of a nut 42. The plate 41 has a hole 43 considerably larger than the diameter of the stud 40 so that the vertical and horizontal position of the upthrust roller 39 can be adjusted to track the roller on the underside of an upper horizontal flange 44 of the bracket 11, thus to prevent the hanger (and the door it supports) from rocking on a horizontal axis parallel to the axis of the wheel 9, which would bind the hanger and interfere with free movement of the door.

Each of the hangers 8 carries a small angle bracket 45 to which is secured a felt pad 46. The felt pad 46 is thoroughly impregnated with lubricant and, Figure IV, slides along the upper surface of the rail 30 to keep it clean of grit and dirt so that a smooth surface is provided for the wheel 9.

At each outermost end of the bracket 11 there is located an idler pulley 14 (Figure III) to return the cable 13 so that the two doors will operate simultaneously. Each of the idler pulleys 14 is rotatably mounted on the end of a stud 47 and retained thereon by a split ring 48. The idler pulleys 14 are grooved to receive the cable 13. As also can be seen in Figure III, the bracket 11 is fixedly secured to the crossframe member 12 by a plurality of machine screws 49 two of which are shown in Figure III.

The vibration of the elevator doors which results from their movement horizontally to and from open and closed positions is first partially insulated by the annular vibration absorbing elements 27 so that certain vibrations are stopped at this point and do not even reach the wheels 9. Other vibrations of greater amplitude such as the slight swaying of the doors are minimized by the upthrust rolls 39 and then insulated from the elevator cab itself by the cushions 37 interposed between the rail retainer 31 and the track mounting member 32. Conversely, any vibrations which may exist in the body of the cab are insulated from the elevator doors by the same two vibration insulating elements in the hanger mechanism embodying the invention.

The simplification of the vibration absorbing mechanism resulting from the use of track elements having interlocking portions which are insulated from each other by the cushions 37 interlocked therewith, results in a structure in which inexpensive extruded parts can be used to form the interlocking vibration absorbing track thus greatly reducing the cost of such a mechanism.

Various changes in the particular shape of the vibration insulating members of the structure may well be made without departure from the subject and scope of the claims.

Having described the invention, I claim:

1. A vibration absorbing track for an elevator door hanger having a rotatably journaled wheel, comprising, an elongated rail on which said wheel runs, a support member extending along the rail and a cushioning member located between said rail and said support member, the cross-sectional shapes of said rail, said support member and said cushioning member being the same through their lengths and having integral laterally extending interlocking flanges, the flanges of said cushioning member being interposed between the flanges of said rail and said support member.

2. A vibration absorbing track for an elevator door hanger, said track comprising a support member, a rail and a cushioning member, said

support member comprising an elongated member having upper and lower flanges extending laterally from the top and bottom of a central vertical web, said rail comprising an elongated body having a generally U-shaped cross section the sides of which loosely embrace the support member and have inwardly directed portions fitting beneath the upper flange of the support member, and said cushioning member comprising elongated resilient members embracing the inwardly directed portions of the rail and being embraced between the upper and lower flanges of the support member, whereby said members and rail are held in assembled relation by the interlocking of the rail portions and support member flanges. 15
